US00D992142S

(12) **United States Design Patent** (10) Patent No.: **US D992,142 S**
(45) Date of Patent: **** Jul. 11, 2023**

(54) **LABORATORY APPARATUS**

(71) Applicant: **IKA-Werke GmbH & Co. KG**,
Staufen (DE)

(72) Inventors: **Matthias Hahnen**, Saarbrücken (DE);
Sebastian Wiegert, Freiburg (DE);
Christian Babel, Freiburg (DE)

(73) Assignee: **IKA-Werke GmbH & Co. KG**,
Staufen (DE)

(**) Term: **15 Years**

(21) Appl. No.: **35/513,463**

(22) Filed: **Nov. 17, 2021**

(80) **Hague Agreement Data**

Int. Filing Date: **Nov. 17, 2021**
Int. Reg. No.: **DM/218489**
Int. Reg. Date: **Nov. 17, 2021**
Int. Reg. Pub. Date: **Jan. 28, 2022**

(51) **LOC (14) Cl.** 24-99

(52) **U.S. Cl.**

USPC **D24/232**

(58) **Field of Classification Search**

USPC D24/220, 232, 231, 221; D7/402, 386;
D15/147
CPC G01G 23/3707; G01G 23/01; B01D 3/02;
B01D 15/08; B01F 31/22; B01F 33/813;
B01F 35/42; B01F 33/862; B01F 31/42;
G05D 23/1919

Primary Examiner — Rhea Shields

(74) Attorney, Agent, or Firm — Volpe Koenig

(57) **CLAIM**

The ornamental design for a laboratory apparatus, as shown and described.

DESCRIPTION

1. Laboratory apparatus
3. Laboratory apparatus
- 1.1 : Top
- 1.2 : Left
- 1.3 : Right
- 1.4 : Back
- 1.5 : Front
- 1.6 : Bottom
- 1.7 : Perspective
- 3.1 : Top
- 3.2 : Left
- 3.3 : Right
- 3.4 : Front
- 3.5 : Back
- 3.6 : Bottom
- 3.7 : Perspective

1 Claim, 14 Drawing Sheets
